UNITED STATES PATENT OFFICE

94,770

DESIGN FOR A CONFECTION WITH SUPPORTING STICK

Norman F. Lucke, Carleton, Mich., assignor to Sol
Decker, Chicago, Ill.

Application August 24, 1934, Serial No. 53,040

Term of patent 14 years

To all whom it may concern:

Be it known that I, Norman F. Lucke, a citizen of the United States, residing at Carleton, in the county of Monroe, State of Michigan, have invented a new, original, and ornamental Design for Confection with Supporting Stick, of which the following is a specification, reference being had to the accompanying drawing, forming a part thereof.

Fig. 1 is an elevational view of a confection with supporting stick showing my new design, and

Fig. 2 is a vertical cross section thereof taken on the line 2—2 of Fig. 1.

The dominant feature of my design is the supporting stick.

I claim:

The ornamental design for a confection with supporting stick as shown and described.

NORMAN F. LUCKE.
